CLAIM

The ornamental design for a paint scraper, as shown and described.

DESCRIPTION

FIG. 1 is a perspective view of a paint scraper showing my new design;

FIG. 2 is a top plan view thereof;

FIG. 3 is a front elevational view thereof, the rear being a mirror image;

FIG. 4 is a bottom plan view thereof;

FIG. 5 is a right-side elevational view thereof; and,

FIG. 6 is a left-side elevational view thereof.

The broken lines in FIG. 1 are for the purpose of illustrating environment and form no part of the claimed design.
